UNITED STATES PATENT OFFICE.

THOMAS W. LANE AND THOMAS W. GLEESON, OF BOSTON, ASSIGNEES TO THEMSELVES AND CHARLES WILLIAMS, JR., OF SOMERVILLE, MASS.

TELEPHONE SWITCH-BOARD.

SPECIFICATION forming part of Letters Patent No. 244,626, dated July 19, 1881.

Application filed May 27, 1881. (No model.)

To all whom it may concern:

Be it known that we, THOMAS W. LANE and THOMAS W. GLEESON, of Boston, in the county of Suffolk and State of Massachusetts, have 5 invented certain Improvements in Telephone Switch-Boards, of which the following is a specification.

This invention relates to that class of switch-boards of which a type is shown in the application of T. W. Lane, filed May 16, 1881, embodying a series of line-circuit strips, each adapted to be turned laterally to separate it from a ground-strip, against which it is normally held with a yielding pressure; a series 15 of connecting-strips, each provided with as many plugs or connecting devices as there are line-circuit strips, said plugs being permanently secured to the connecting-strips and normally disconnected from the line-circuit strips, and adapted to make contact with the line-circuit strips, and at the same time to engage with and hold said strips from the ground-strips; and, finally, means for disengaging the line-circuit strips from the plugs of the connecting-strips, and permitting said plugs and strips to automatically resume their normal position.

The invention consists in certain improvements in the construction of the line-circuit strips of a switch-board of this class, whereby 30 said strips are enabled to be securely engaged with the plugs of the connecting-strips and conveniently turned to disengage said plugs, as we will now proceed to describe and claim.

35 Of the accompanying drawings, forming part of this specification, Figure 1 represents a plan view of a switch-board embodying our improvements. Fig. 2 represents a section on line xx , Fig. 1. Fig. 3 represents a section on line yy , Fig. 1. Figs. 4, 5, and 6 represent enlarged views of parts in detail.

The same letters indicate the same parts in all the figures.

In the drawings, B represents a switch-board 45 having a series of line-circuit strips, a , and a ground-strip, c , common to all the line-circuit strips. Each strip a is composed of a tube adapted to rotate on a rod, b , rigidly attached to one side of the frame of the switch-board. 50 Each strip a projects through the opposite side

of the switch-board, and is provided with a knob or handle, a' , by which it may be turned. The strips a are provided with projections m , which are held with yielding pressure against the ground-strip c by springs s , connected to 55 the strips a and the frame of the switch-board. The connecting-strips d are, as usual, arranged at right angles to the line-circuit strips, and are insulated therefrom by the frame of the switch-board, to which they are rigidly attached. Each strip d has a series of plugs or 60 connecting devices, e , there being as many of said plugs in each strip d as there are line-circuit strips. These plugs are movable longitudinally toward and from the line-circuit 65 strips, and are normally held away from said strips by springs f , but are adapted to be forced inwardly against the pressure of said springs. Each plug e has a notch or recess, n , formed in the lower portion of its shank, and a shoulder or projection, h , on the lower end. The tubular line-circuit strips a are provided with orifices i , which correspond in number to the plugs e , and are adapted to coincide with and receive the notched ends of said plugs when 70 the strips a are turned away from the ground-strip c , the rods b being flattened on one side 75 to form cavities under the orifices i , to receive the ends of the plugs when the latter are pushed inwardly. When one of the plugs e is inserted in one of the orifices i one edge of the orifice is pressed by the spring s into the notch n back of the shoulder h , so that the plug and strip are mutually held in contact with each 80 other, and neither can resume its normal position, the line-circuit strip being disconnected from the ground-strip.

The general operation of connecting the circuits by the switch-board is effected in the usual manner—that is to say, when a subscriber on one of the line-circuit strips (say No. 6) wishes to communicate with another (say on No. 1) the line-circuit strips corresponding to said circuits are turned by the operator to bring the orifices i under the plugs e , and two 90 plugs on any unoccupied connecting-strips are pushed into the orifices corresponding to said plugs, the strips a being held by the operator until the plugs are inserted, and then released, so that the strips can hold the plugs, as already 95 100

described. The two circuits are thus connected so that the subscribers can communicate. When it is desired to break the connection the operator turns each line-circuit strip until the plug held thereby is released and retracted by its spring *f*, and then releases the strip, so that its spring *s* will turn it back to contact with the ground-strip.

We do not claim, broadly, the combination of the line-circuit strips, each normally held in contact with a ground-strip and adapted to be separated from the latter, and the connecting-strips, each having as many spring-retracted plugs or connecting devices as there are line-circuit strips, such combination being the sole invention of Thomas W. Lane, and shown in the application above referred to.

We claim—

In a switch-board, the line-circuit strips, each composed of a perforated rotary tube, *a*, held in yielding contact with a ground-strip, and a fixed supporting-rod, *b*, combined with the connecting-strips, each having a series of spring-retracted notched plugs, *c*, all arranged and operating substantially as described. 25

In testimony whereof we have signed our names to this specification, in the presence of two subscribing witnesses, this 24th day of May, A. D. 1881.

THOMAS W. LANE.
THOMAS W. GLEESON.
